Patented Aug. 9, 1921.

Arthur S. Peck.

By Arthur Brown.

Attorney

UNITED STATES PATENT OFFICE.

ARTHUR S. PECK, OF LAWRENCE, KANSAS, ASSIGNOR TO LAWRENCE PAPER MANUFACTURING COMPANY, OF LAWRENCE, KANSAS, A PARTNERSHIP COMPOSED OF M. G. BOWERSOCK, IRVING HILL, PAUL A. DINSMOOR, HORTENSE B. HILL, MARY B. DINSMOOR, JEAN B. BLACKWELDER, AND MARGERY B. DALTON.

CADDY-BOX.

1,387,167.

Specification of Letters Patent. Patented Aug. 9, 1921.

Application filed March 22, 1920. Serial No. 367,671.

To all whom it may concern:

Be it known that I, ARTHUR S. PECK, a citizen of the United States, residing at Lawrence, in the county of Douglas and State of Kansas, have invented certain new and useful Improvements in Caddy-Boxes; and I do declare the following to be a full, clear, and exact description of the invention, such as will enable others skilled in the art to which it appertains to make and use the same; reference being had to the accompanying drawings, and to the letters and figures of reference marked thereon, which form a part of this specification.

This invention relates to a caddy box; that is, a container from which farinaceous materials such as cakes, crackers or the like may be dispensed, the principal object of the invention being to provide a box of this character in which the contents are protected from dust, dirt, insects and the like, while on a shelf, but which may be easily and quickly opened when the contents are to be removed.

The box is preferably constructed of flexible material, such as straw board, paperoid, paper or fiber board and comprises flaps adapted to coöperate to frictionally hold a swinging cover in closed position, and for sealing the opening when the cover is closed.

In the drawings,

Figure I is a perspective view of a caddy box constructed in accordance with my invention.

Fig. II is a cross sectional view through one end and a part of the cover, showing the frictionally engaging meeting flaps of the cover and end, and

Fig. III is a cross sectional view through one of the sides of the box and cover, showing a sealing flap in sealing position.

The box may be constructed in any suitable manner to comprise the sides 1 and 2, the ends 3 and 4, and the bottom 5. The ends 3 and 4 have inturned flaps 6, to which the inturned flaps 7 and 8 of the sides 1 and 2 are secured in the usual manner, a preferred construction being one in which the back 3 and the body part are formed from separate blanks and connected by adhesive strips 9, although this detail of construction is unimportant.

Forming part of one of the end walls, for example, the back 3, is a cover or top 10, which is foldable relative to the wall 3 to swing into and out of closing position. The cover 10 is provided with straight side edges and with a yielding, depending flap 11, having a friction face 12 to engage a friction face 13 on the yielding inner projecting flap 14 carried by the front end wall 4.

The sides 1 and 2 are provided with inwardly projecting sealing flaps 16 and 17, which are adapted to lie snugly against the inner face of the cover 10. When the cover is in sealing position, the flap 13 has a tendency to project downwardly while the flaps 16 and 17 tend to extend in an upward, inclined position, as clearly shown in Fig. I. When the cover 10 is moved into closing position, the face 12 of the flap 11 will contact with the face 13 of the flap 14 and since the flap 14 tends to spring inwardly, due to the resilient connection with the wall 4, and since the flap 11 tends to spring outwardly, due to its resilient connection with the cover 10, the two flaps will bear one against the other with sufficient pressure to cause a frictional contact to hold the cover 10 in closed position. In other words, the flaps 11 and 14 constitute a lock for the cover 10, since the flaps 16 and 17 have a tendency to press upwardly as soon as the cover 10 is in closed position. These flaps 16 and 17 will bear against the under face of the cover 10 but not with sufficient pressure to cause a release of the cover flap 11 from the flap 14. It will be apparent, though, that the upward pressure of the flaps 16 and 17 and the inward pressure of the flap 14 will cause the box to be sealed around the entire edge of the opening 18 when the opening is closed by the cover 10. Therefore, the box will be sealed against dust, dirt, insects and other objectionable matter and an efficient temporary seal will be provided without the necessity of employing special fastening devices.

I am aware that boxes of this general construction have been formed with inwardly projecting flaps on the walls thereof which coöperate with inwardly projecting flaps on a cover, but I am not aware that

previous to my invention it has been contemplated to provide a cover with a friction flap adapted to engage a complementary flap on the end of the box to hold it in closed position, nor to provide upwardly projecting side flaps coöperating with those just described so as to constitute a seal.

While I have described a form of the invention wherein the cover or sealing end is located at the top of the box, such specific location is not intended as a limitation of the scope of the invention, as the cover may be located on any end or side of the box, or more than one may be employed, if desired.

15 What I claim and desire to secure by Letters-Patent is:

1. A caddy box consisting of a bottom, sides and ends with a swinging cover carried by one of the ends, inwardly projecting, yielding flaps on the upper edges of the sides, a flap on one end of the box and beneath the side flaps, and a depending flap on the free edge of the cover having a friction face for engagement with the face of the flap 25 on the end of the box.

2. A caddy box consisting of a bottom,

sides, ends and a swinging cover connected to the upper edge of the box, an inturned, friction flap on the end of the box, and a depending friction flap carried by the cover 30 and engaging the inturned flap on the end of the box, whereby the box cover will be held in closed position.

3. As a new article of manufacture, a box consisting of sides, a bottom and ends, an integral cover on one of the ends having a depending flap, and an inwardly projecting flap on the end of the box opposite to that supporting the cover, said flaps coöperating by frictional contact to secure the cover in 40 closed position.

4. A caddy box consisting of a bottom, sides and ends, a cover yieldingly supported by one end of the box and having straight sides with a depending flap at its free end, 45 a coöperating flap carried by one end of the box and frictionally engageable with the flap on the cover, and inturned, upwardly disposed side flaps carried by the box.

In testimony whereof I affix my signature. 50

ARTHUR S. PECK.
